UNITED STATES PATENT OFFICE.

JOHN M. HOPWOOD, OF DORMONT, PENNSYLVANIA, ASSIGNOR TO DARWIN S. WOLCOTT,
TRUSTEE, OF SEWICKLEY, PENNSYLVANIA.

HOLLOW GRATE-BAR.

1,330,536.

Specification of Letters Patent. Patented Feb. 10, 1920.

Application filed October 9, 1917. Serial No. 195,527.

To all whom it may concern:

Be it known that I, JOHN M. HOPWOOD, residing at Dormont, in the county of Allegheny and State of Pennsylvania, a citizen 5 of the United States, have invented or discovered certain new and useful Improvements in Hollow Grate-Bars, of which improvement the following is a specification.

The invention described herein relates to 10 the introduction of air below fuel supporting members and its discharge through between such members and its distribution in such manner as to insure practically uniform combustion at all points of the bed of 15 fuel. The invention is hereinafter more fully described and claimed.

In the accompanying drawings forming a part of this specification, Figure 1 is a sectional plan view of a boiler fire-box on a 20 horizontal plane above the grate bars; Figs. 2 and 3 are vertical sections on planes indicated respectively by the lines II—II and III—III, Fig. 1; Fig. 4 is a view similar to Fig. 2, illustrating a modification of the 25 improvement; Fig. 5 is a sectional detail view illustrating a modification of the construction of the grate bars; Fig. 6 shows transverse sections of the grate bars, of a modified form or construction of bar.

30 In the practice of the invention, the grate bars 1, the construction of which will be hereinafter described, extend from the fuel charging or front end of the furnace toward the rear end thereof and are supported in an 35 inclined position by flanges 2 at opposite ends of the wind box 3, and by vertical wall 4 extending across the box as clearly shown in Figs. 1 and 2. The box 3 is preferably made of metal and of such horizontal di- 40 mensions as to completely fill the fire box or furnace chamber except at the rear end thereof, where a sufficient space is provided for the dump plate on to which the ashes are discharged from the rear ends of the 45 grate bars. The grate bars are made hollow and are provided at or near their middle portions with openings 5, arranged on opposite sides of the transverse wall 6. In the construction shown in Figs. 1, 2 and 3, these 50 openings serve as inlets so that air entering the respective openings will flow to opposite

ends of the grate bars and escape through outlets 7 into chambers 8 in the wind box. In the constructions shown in Figs. 1, 2, and 3, air is supplied to passages in the grate 55 bars through the channel 9 formed between the transverse partitions 4, the openings 5 connecting with such channel. This channel is connected at one or both ends to flues 10, for conducting air under pressure from 60 a suitable source to the channel. The flow of air through the ports 5 to the respective ends and opposite ends of the grate bars is regulated by valves 11.

From the chambers 8 the air passes up 65 through the spaces between adjacent bars into the fuel lying thereon. The fuel is forced through the neck or opening 12 and onto the grate bars by any suitable fuel feeding means known in the art, and is 70 caused to move toward the rear end of the fire chamber and onto the dump plate 13 by a suitable reciprocation of the grate bars or by any other suitable means. When the movement of the fuel is to be effected by 75 reciprocating the grate bars, the movable bars are merely supported by the flanges 2 and the walls 4, while the alternate bars are held from movement by any suitable means, as for example, by lugs 14 projecting into 80 holes in the front flange 2. The reciprocating bars may be connected to their operating mechanism through the lugs 15 as shown in Fig. 5 or by any other suitable device.

85 The fuel will naturally bank up on the front ends of the grate bars and will diminish in depths toward the rear of the grate bars, and hence there will be a greater generation of gases at the front of the fire 90 box than at other points, due not only to the heating of the green fuel, but also to the larger mass of fuel on the front portions of the grate bars. This generation of large quantities of gases at the front of the fire 95 box necessitates the feeding of larger quantities of air at that point to insure thorough combustion, and hence it is preferred to perforate the walls of the front portions of the grate bars as shown at 16 so that jets of 100 air may be forced direct from the passages in the grate bars to the banked up fuel.

In case air in sufficient quantity to effect the desired combustion at the front of the fire box cannot be supplied through the perforations 16, an auxiliary air chamber 17 5 may be arranged above the neck 12, the wall of such chamber against which the fuel will be banked, being perforated as shown in Fig. 2. This chamber 17 has inlet openings 18 at one or both ends, connected to a suitable source of air under pressure.

If desired, the upper surfaces of the reciprocating grate bars may be stepped as shown in Fig. 5, so as to impart a positive push on the fuel. When employing this stepped 15 construction, perforations may be formed through the shoulders 19 for the escape of air into the superincumbent fuel. As shown in Fig. 5, the grate bars may be made in sections adapted to be connected by bolts when 20 in use, thereby enabling the renewal of burnt out portions of the bars.

In some cases it is desirable to reverse the direction of flow of air through the grate bars and in such cases the wind box 3 is provided at its ends with conduits 20 adapted 25 to be connected to a suitable source of supply of air under pressure. The walls at the upper ends of these passages are constructed to form supports for the ends of the bars 30 permitting of the reciprocation without moving the openings 7 into the passages through the bars out of register with the conduits 20. The air under pressure, the flow of which is regulated by dampers 21, 35 flows through passages 20 and inlet ports 7 into and along the passages in the grate bars and through ports 5 into the chambers 8 in the wind-box. The air under pressure flows from the chambers up between the spaced 40 bars and through the superincumbent bed of fuel. By suitably shifting the dampers controlling the flow of air into the bars, the quantity and pressure of air supplied to the upper and lower portions of the fuel bed 45 can be adjusted as desired.

It is characteristic of the invention described herein that provision is made for distribution of the air supplied for maintaining combustion in different parts of the 50 fuel bed as conditions, *i. e.*, rate of combustion and thickness of fuel bed, may require.

I claim herein as my invention:

1. In a stoking mechanism the combination of a fire box, spaced grate bars arranged 55 in the fire box parallel with the direction of movement of fuel, each of a plurality of the bars having independent longitudinal passages, each passage having an inlet and an outlet port, independent wind boxes arranged 60 under the grate bars, the outlet ports of each of the grate bars being connected to the respective boxes, means for connecting the inlet ports of the bars to a source of air supply, and means for regulating the pressure of air in the respective wind boxes,

whereby the pressure of air supplied to different portions of the fuel bed may be regulated in accordance with the depth of fuel on such portions.

2. In a stoking mechanism the combination 70 of spaced fuel supporting members, each of a plurality of said members having passages extending longitudinally thereof, each of said passages having an inlet and an outlet port, means for forcing air through 75 said passages, means for conducting air from the outlet ports of the passages of each bar to the spaces between adjacent fuel supporting members and means for varying the pressure of the air delivered at different 80 points of the spaces between the fuel supporting members.

3. In a stoking mechanism, the combination 85 of a wind box having independent chambers, spaced grate bars arranged above the wind box and having non-connected longitudinal passages therein, each of said passages having inlet and outlet ports, the outlet ports being adapted to discharge into the respective chambers of the wind box, means 90 for connecting the inlet ports of the grate bars to a source of supply under pressure, and means controlling the flow of air through the inlet ports.

4. In a stoking mechanism, the combination 95 of a wind box, spaced partitions extending across the wind box and dividing the same into independent chambers and forming between them a channel adapted to be connected to a source of supply of air 100 under pressure spaced grate bars arranged above the wind box and having independent longitudinal passages therein, ports connecting the passages in the grate bars to the supply channel, outlet ports adapted to discharge from the passages in the bars into the respective chambers of the wind box, and valves controlling the flow of the air through the grate bars.

5. In a stoking mechanism, the combination 110 of a wind box, having independent chambers therein, spaced grate bars extending across the wind box and having independent longitudinal passages, each passage having an inlet port adapted to be connected to a source of supply of air under pressure, ports adjacent to the ends of the bars connecting the passages in the bars with the chambers in the wind box, valves controlling the flow of air through the grate bars, 120 the grate bars being perforated adjacent to one end to direct jets of air into the fuel lying on the bars.

6. In a furnace having a fuel charging opening, the combination of a wind box having independent chambers therein, spaced grate bars supported by the wind box each bar having independent longitudinal passages therein, each passage having an inlet port adapted to be connected to a source of 130

supply of air under pressure, ports connecting the passages in the bars to the respective chambers in the wind box, the front ends of the bars having perforations for directing jets of air into the fuel lying on the bars, valves controlling the flow of air through the grate bars, and an auxiliary

wind box arranged above the fuel opening into the furnace, and having perforations for directing jets of air into fuel lying on 10 the front portions of the grate bars.

In testimony whereof I have hereunto set my hand.

JOHN M. HOPWOOD.
